SHAVING IMPLEMENT

John L. Nilson, Chicago, Ill.

Application March 17, 1937, Serial No. 131,280

5 Claims. (Cl. 30—43)

My invention relates to a shaving implement adapted for use as a dry shaver of the motor driven type.

Among the objects of my invention are to provide a shaving implement adapted to give to the user a very close shave; to provide a shaving implement having a combined guard and guide member for positioning the shaving implement on the user's face at the proper angle for a close shave and also preventing the implement from cutting the face of the user and at the same time protecting the implement from injury; to create a shaving implement having resilient means for permitting the inner comb to reciprocate against the stationary comb without friction between the reciprocating comb and the resilient member, said resilient member surrounding the driving shaft so as to prevent chattering and to insure an evenly directed pressure on the reciprocating comb; to create a shaving implement which is substantially non-clogging, its parts being so arranged that there are no portions for the retention of clipped hair; to supply a shaving implement more simple in construction and economical of manufacture, and such other objects, advantages and capabilities as will later more fully appear and which are inherently possessed by my invention.

While I have shown in the accompanying drawing a preferred embodiment of my invention, yet I wish it understood that the same is susceptible of modification and change without departing from the spirit of my invention.

Fig. 1 is a perspective view of my shaving implement with a portion broken away to show the motor; Fig. 2 is a front view of the head of my shaving implement with the retaining plate partly broken away and showing the top portion of the driving mechanism; Fig. 3 is a side view of the structure shown in Fig. 2; Fig. 4 is a plan detail view, and Fig. 5 is a side view of my spring retaining bearing or button. Fig. 6 is a front detail view of my inner reciprocating comb and Fig. 7 is a side view of the same.

The implement selected to illustrate my invention comprises a hollow handle 10 in which is arranged in any suitable manner an electric motor 11 adapted to be connected to an electrical source of supply by lead wires 12. The motor 11 has a driving shaft 13 ending in an eccentric 14 adapted to engage a head 15.

My head 15 comprises a base 16 to which is attached by suitable means such as screws 17, an outer angle plate 18, the shorter bent portion of which forms a stationary comb 19. An inner angle plate 20 is positioned within the interior

portion of the outer angle plate 18, the shorter bent portion of said inner angle plate 20 forming a reciprocating comb 21. A resilient member 22 has one end seated in a recess 23 in the base 16. The other end of the resilient member 22 engages a recess 24 in a button or spring retaining bearing 25. Said button 25 has thrust bearings 26 adapted to lie against a pair of lugs 27, said lugs 27 formed from a cutout portion 28 in portion 29 of inner angle plate 20. Said button 25 also has a hub 30 adapted to fit between said lugs 27 for imparting reciprocating movement to the reciprocating comb 21.

A retaining plate 31 has one end attached by suitable means such as screws 32 to the base 16 18 and has a portion 33 bent at a right angle to bear against the inner angle plate 20 to hold the inner angle plate 20 against the outer angle plate 18, and for sealing the moving mechanism so that it is protected from cut hair, cuticle matter or 20 the like.

The outer angle plate 18 has a comb 19, the teeth 34 of which form parallel cutting edges 35. The comb 19 remains in a stationary position. In the comb 21 which lies against the inner side 25 of the stationary comb 19, the teeth 36 form parallel cutting edges 37. Said inner comb 21 is adapted to be moved in a reciprocating movement through the following construction: The driving shaft 13 passes through an aperture 38 in the base 30 16 and extends so that the eccentric 14 is engaged in an elongated pocket 39 in button 25. As the eccentric 14 is actuated and moves the button 25, the hub 30 of the button moves the inner comb 21 in a reciprocating movement across the inner 35 surface of the outer comb 19.

The outer comb 19 is knife blade or wedge shaped in that it tapers to an extremely thin front edge 40. The comb 19 having such a thin edge, permits the user to obtain a shave at least 40 as close as the infinitesimal thickness of said thin edge. Because the comb 19 is so thin at its maximum close shaving contact position, it is desirable for general use to employ a guard guide 41 which I provide in the shape of a substantially 45 U-shaped member, the ends 42 of which removably and frictionally fit into apertures 43 in oppositely disposed sides of the base 16. The connecting portion 44 of the U-shaped guard guide is spaced from the edges of the combs so that a 50 user is guided into a position for a correct close shave and at the same time is guarded against danger from cutting due to too close a shave. The guard guide also protects the combs from 55 injury.

The inner exposed face 45 of my reciprocating comb 21 permits the free and immediate escape of cut hair. My head 15 is so constructed that it has open front and sides adjacent the inner exposed face 45 of my reciprocating comb 21. There are no pockets into which cut hair may accumulate to clog and even stall working parts. My head having no such pockets, needs no extraneous cleaning devices for the removal of cut hair.

In the construction of my device, I provide centrally located pressure on the reciprocating comb 21 which in turn imparts pressure or thrust against the stationary comb 19 by means of my resilient member 22. This resilient member 22 surrounds that portion of the driving shaft 13 between the base 16 and the button 25 thereby providing frictionless pressure to the reciprocating comb 21. My resilient member 22 has clearance of the driving shaft 13 substantially greater than the stroke of the reciprocating comb 21 so that the resilient member 22 may oscillate free from contact with the driving shaft 13. My resilient member 22 engaging the recess 24 of the button 25 is capable of lateral as well as thrust movement, thus eliminating any frictional contacts.

In operation the hair of a person shaving enters the slots 46 of comb 19 and the slots 47 of comb 21, and are clipped by the reciprocating action of the inner comb 21 against the outer comb 19.

Having thus described my invention, I claim:

1. A shaving implement comprising a base, a stationary comb attached to said base, a movable comb positioned against said stationary comb, said movable comb having an inner exposed face so as to permit free escape of cut hair, means for reciprocating said movable comb so that the teeth of said movable comb operate transversely to the openings in the stationary comb, and a retaining plate attached to said base on one end, and bent to contact at its other end said movable member and hold said movable member against said stationary member, said retaining plate also protecting the inner parts of the shaving implement from cut hair.

2. In a shaving implement having a stationary member with transverse teeth spaced by transverse openings, and a movable member with transverse teeth spaced by transverse openings, said movable member adapted to be reciprocated across said stationary member by a power driven driving shaft ending in an eccentric, a base, a resilient member having one end seated in said base, a bearing contacting said movable member, the other end of said resilient member contacting said bearing, and applying centrally positioned frictionless pressure on said movable member for holding it against said stationary member, said bearing having an elongated pocket to receive the eccentric, said bearing upon being moved by said eccentric moving in turn said movable member.

said resilient member surrounding the driving shaft between the base and the bearing and adapted to oscillate free from contact with the driving shaft.

3. A shaving implement comprising a hollow handle, a motor positioned within said handle, lead wires leading from said motor to a source of power, a shaving head comprising a base, an outer angle plate attached to said base, the shorter portion of said angle plate formed as a comb, an inner angle plate positioned against the inside of said outer angle plate, the shorter portion of said angle plate formed as a comb, a retaining angle plate attached to said base, the shorter end of said angle plate contacting the inner angle plate to hold the same against the outer angle plate and for protecting the driving shaft and an eccentric of the motor from exposure to injury, said base having a centrally located aperture for the passage therethrough of the driving shaft, a resilient member, a bearing contacting said inner angle plate, one end of said resilient member seated in said base, and the other end contacting said bearing to impart pressure to the bearing which in turn imparts pressure to said inner angle plate for centrally positioning it against the outer angle plate, said bearing having an elongated pocket, said eccentric positioned in said pocket and adapted upon movement of the drive shaft to move said bearing, which in turn moves said inner angle plate and its comb across the comb of the stationary outer angle plate, said resilient member spaced from the driving shaft and surrounding the same between the base and the bearing and adapted upon movement of the driving shaft to oscillate free from contact with the driving shaft.

4. A shaving implement comprising a stationary comb, a movable comb positioned against said stationary comb, a driving shaft adapted to reciprocate said movable comb so that the teeth of said movable comb operate transversely to the openings in said stationary comb, and a resilient member surrounding said driving shaft and adapted to oscillate in both a lateral and thrust movement free from contact with said driving shaft for applying frictionless pressure to the movable comb.

5. A shaving implement comprising a stationary comb, a movable comb positioned against said stationary comb, a driving shaft adapted to reciprocate said movable comb so that the teeth of said movable comb operate transversely to the openings in said stationary comb, and a resilient member surrounding said driving shaft and adapted to oscillate in a lateral and forward movement to a greater degree than said movable comb, said resilient member oscillating free of the driving shaft so that it exerts frictionless pressure to hold said movable comb against said stationary comb.

JOHN L. NILSON.
